UNITED STATES PATENT OFFICE.

LAWRENCE GRIFFITH, OF YONKERS, NEW YORK.

INSULATED RAIL-JOINT.

1,107,666.

Specification of Letters Patent. Patented Aug. 18, 1914.

Application filed March 20, 1913. Serial No. 755,601.

To all whom it may concern:

Be it known that I, LAWRENCE GRIFFITH, a citizen of the United States, and resident of Yonkers, in the county of Westchester, State of New York, have invented certain new and useful Improvements in Insulated Rail-Joints, of which the following is a specification.

One of the main objects of this invention is to provide a rail joint which may be used in connection with tie plates under rail ends without the necessity of placing insulating material between said tie plates and the rails.

15 It is the common practice in insulated rail joints where tie plates are used to insert a strip of fiber or other suitable hard insulating material between the rail base and the tie plate. This is objectionable for the reason that the insulation is soon disintegrated and destroyed by the constant hammering or pounding of the rail thereon. It is manifest, therefore, that to provide an efficient insulated rail joint in which tie plates may be used, said plates and the rails being in direct contact, is very desirable. The use of tie plates has become practically universal in modern railroad building and it becomes practically necessary, therefore, 20 to use tie plates under the rail joints.

Another object of the invention is to provide a tie plate especially adapted for improved rail joint construction.

Another object of the invention is to provide an insulating strip or sheet of peculiar form for use in the insulated rail joint and also to provide a short metal filler piece to be used in connection with the insulating strip or sheet.

40 Another object of the invention is to so arrange the insulating sheet and the metal filler piece that the metal filler piece will receive a large portion of the wear occasioned by the hammering of the car wheels as they cross the joint or space between the rail ends.

Another object of the invention is to construct and arrange the metal filler and the insulating strip or sheet so that the insulation may be removed from between the splice bar and the rails without disturbing the metal filler piece. This is important as it permits of the replacement of the insulating material without a complete disorganization of the joint.

There are other important objects and advantages of the invention which will appear hereinafter.

In the drawing, Figure 1 is a transverse vertical sectional view of the joint on the line I—I of Fig. 3; Fig. 2 a similar view on the line II—II of Fig. 3; Fig. 3 a side elevation of the joint; and Fig. 4 a perspective view of the insulating sheet and the filler piece, these parts being shown in the relative positions which they occupy in the assembled joint.

Referring to the various parts by numerals, 1 and 2 designate the rail ends which are separated by the usual insert of insulation 3. Under the rail 1 is arranged a tie plate 4 and under the rail 2 is arranged a tie plate 5. These tie plates are broad and extend a considerable distance outwardly beyond the longitudinal edges of the rail bases. The tie plate 4 is formed with an upwardly extending shoulder 6 which is adapted to bear against the longitudinal edge of the base of rail 1; and the tie plate 5 is formed with a similar shoulder 7 which is adapted to engage the longitudinal edge of the base of the rail 2.

Splice bars 8 and 9 are employed; and said splice bars are formed with outwardly extending base flanges 10 and 11, said flanges extending outwardly a considerable distance beyond the longitudinal edges of the bases of the rails, as shown clearly in Figs. 1 and 2. Interposed between the splice bars and the rails are insulating strips or sheets 12 and 13, the insulation 12 being interposed between the splice bar 8 and the rails and the insulation 13 being interposed between the splice bar 9 and the rails. Each insulating sheet is formed with the vertical web 14; the upwardly and outwardly extending member 15 which is adapted to fit between the upper surface of the splice bar and the under side of the rail head, and with the downwardly and outwardly extending member 16 which is adapted to fit between the base flanges of the splice bar and the upper surface of the base of the rail. The upper member 15 and the vertical web portion 14 of each insulating sheet is cut away at one end, as shown clearly in Figs. 3 and 4, the upper edge of the remaining portion fitting under the bolts connecting the adjacent splice bar to one of the rails, the bolts securing the splice bar to the other

105 110

rail passing through openings in the web of the insulating sheet. This construction and arrangement of parts is shown clearly in Figs. 3 and 4. Fitting in the cut out part of the insulating sheet and taking the place of the cut out portion of said sheet is a metal filler piece 17. This filler piece is in the form of a steel strip or sheet bent to conform to the shape of the removed part of the insulating sheet. This filler piece has an upwardly and outwardly extending member 18 which fits between the upper surface of the splice bar and the under surface of the rail head; and has a vertical web portion 19 which extends below the joint bolts and is provided with suitable apertures for the passage of said bolts. This steel filler is of the same thickness as the insulating sheet.

20 The tie plates are provided with openings 20 and 21 for the passage of the spikes which secure the joint to the ties. The apertures 20 are smaller than the apertures 21, and are so arranged that the spikes 22 contact with one edge thereof and draw or force the shoulders 7 and 6 against the longitudinal edges of the rail bases. The spikes 22 are in direct contact with the tie plates. In the apertures 21 are arranged insulating bushings 23 and through the bushings spikes 24 are driven. It is manifest that said insulating bushings insulate the spikes 24 from the tie plates. The spikes 22 and 24 are out of direct contact with the rails and only the spikes 22 are in electrical connection therewith through the tie plates.

The splice bar 8 is completely insulated from the rail 2 and the tie plate 5 on which said rail rests. Joint bolts 25 are insulated from the splice bar 8 and rail 2; and joint bolts 26 are insulated from splice bar 9, rail 1 and tie plate 4. It is manifest that as rail 1 rests directly on tie plate 4 it is unnecessary to insulate splice bar 8 from said rail or said tie plate in view of the fact that said splice bar is completely insulated from rail 2 and its tie plate. It is also manifest that as rail 2 rests directly on tie plate 5 it is unnecessary to insulate splice bar 9 from said rail in view of the fact that said splice bar is completely insulated from rail 1.

It is obvious that I provide an insulated rail joint in which a minimum amount of insulating material is used and at the same time provide tie plates under each rail which are in direct electrical contact therewith. The metal filler pieces 17 receive the greater part of the strain occasioned by the passing car wheels and to a large extent prevent the disintegration of the fiber arranged between the head of the rail and the splice bar. This filler piece is particularly effective in preventing the disintegration of the fiber when arranged as shown, for the reason that the rail rests directly on the metal tie plates.

This gives a very rigid support for the rail ends, the entire joint being practically as rigid as a non-insulated joint provided with tie plates.

The filler pieces are approximately one-half the length of the splice bars and receive all of the bolts passing through one rail. By reason of this arrangement it will be unnecessary to completely dismantle the joint when renewing the fiber parts. If it be desired to remove the insulation 12 it is only necessary to remove joint bolts 25 and slightly loosen joint bolts 26. The insulation 12 may then be removed and a new piece inserted and the bolts 25 replaced. If it then be desired to remove the insulation 13 joint bolts 26 may be removed thus permitting the insulation 13 to be slid lengthwise from the joint and a new sheet inserted. It is thus manifest that at all times one side of the joint bolts and both splice bars may be maintained in position in the joint. It is, of course, necessary to draw the spikes from splice bar 8 when removing the insulation 12; and to remove the spikes from splice bar 9 when removing the insulation 13.

It is manifest that by my construction and arrangement of insulation and filler pieces, said pieces are reversible and may be used on either side of the rail. It is also clear that the filler pieces and the insulation material for both sides of the rail are of the same shape and dimensions. This facilitates the manufacture of the parts and renders the assembling of the joint a simple matter which can be readily accomplished. There is no special selection of parts required, it being only necessary to arrange the insulation and the filler pieces so that they will be oppositely disposed or in staggered relation to each other.

What I claim is:

1. An insulated rail joint comprising a pair of splice-bars, insulating material between the splice-bars and the rails, a pair of tie plates one for each rail end and in direct electrical contact therewith, a metal filler piece for each rail end and arranged between the rail and the upper surface of the splice-bar, said filler pieces being arranged on opposite sides of the rail, means for securing one end of each splice-bar to a tie, said securing means being out of contact with the adjoining tie plate.

2. An insulated rail joint comprising a pair of splice-bars, rail ends, insulating material between said rail ends and the splice-bars, one of said rails being completely insulated from one splice-bar and the other rail being completely insulated from the other splice-bar, a metal filler piece interposed between each rail end and a splice-bar, said filler pieces being on opposite sides of the rails and at opposite ends of the joint.

8 tie plate under each rail and in direct electrical contact therewith, means for securing the completely insulated splice-bar to a tie, said means being out of contact with the adjoining tie plate.

9. An insulated rail joint comprising the meeting ends of two rails, a pair of splice-bars, a tie plate under each rail in direct electrical contact therewith, a shoulder on 10 each tie plate engaging the longitudinal edge of the rail base, insulating material between the splice-bars and the rails, one of said splice-bars being completely insulated 15 from the rail, the other splice-bar being completely insulated from the other rail, metal filler pieces being arranged between each rail and the splice-bar, said filler pieces corresponding in thickness to the insulation at the opposite side of the rail, means for 20 securing the completely insulated end of each splice-bar to a tie, said means being out of contact with the adjoining tie plate, and means for securing the adjacent end of the opposite splice-bar to a tie, said means 25 engaging the tie plate and forcing the shoulder therein against the rail base.

10. An insulated rail joint comprising the meeting ends of two rails, a pair of splice-bars, a tie plate under each rail, a shoulder 20 on each tie plate engaging the longitudinal edge of the rail base, insulating sheet between the splice-bars and the rails, each of said insulating sheet being formed with a vertical web portion, an inwardly and outwardly extending part and a lower downwardly and outwardly extending part, the web and the upper and outwardly extending part of each sheet being cut away 25 at one end, the downwardly and outwardly extending part being approximately equal in length to the splice-bar, a metal filler piece 30 corresponding in thickness to the insulation at the adjoining rail, said filler piece being formed with a vertical web portion, an inwardly and outwardly extending part and a lower downwardly and outwardly extending part, the web portion and the upper and outwardly extending part being cut away for approximately one-half of the 35 length of the sheet, the lower downwardly and outwardly extending portion extending the full length of the web portion, and a metal 40 filler piece of approximately the same thickness as the insulation sheet, said insulation sheet and the metal filler piece being formed with a vertical web portion, said web portion 45 an upwardly and outwardly extending part and a vertical web portion, said web portion

being apertured for the passage of the joint bolts.

5. An insulated rail joint comprising the meeting ends of two rails, a pair of splice-bars, insulating material between the splice-bars and the rails, a pair of shouldered tie plates one for each rail end, and in direct electrical contact therewith, said tie plates extending outwardly beyond the edges of the splice-bars, a metal filler piece for each rail end and arranged between the rails and the upper surfaces of the splice bars, said filler pieces being arranged on opposite sides of the rails and on opposite sides of the division between the rails, means for 70 securing the insulated end of each splice-bar to a tie, said means being out of contact with the rail and the tie plate, and securing means for the non-insulated end of each splice-bar, said means passing through the 75 tie plate.

6. An insulated rail joint comprising a pair of splice-bars, rail ends, insulating material between said rail ends and the splice-bars, one of said rails being completely 80 insulated from one splice-bar and the other rail being completely insulated from the other splice-bar, a metal filler piece interposed between each rail end and the splice-bar, said filler pieces being on opposite sides of the rails and at opposite ends of the joint, a shoulder of tie plate under each rail end and in direct electrical contact therewith, said tie plates extending outwardly beyond the edges of the splice-bars, means for 85 securing the completely insulated splice-bar to a tie, said means passing through but being completely out of contact with the adjoining tie plate, means for securing the non-insulated ends of the splice-bars to a tie, said 90 means passing through the tie plate.

7. An insulated rail joint including two rail ends, two joint bars, a metal filler between one rail head and one joint, a corresponding metal filler between the other rail head and the other joint bar, insulation for the joint bars including a head section between each bar and one rail head, one of 100 said head sections being directly opposite the metal filler and an insulating base section between each joint bar and the flanges of both rails, said base section being integral with the adjoining head section, the metal fillers being in staggered relation on opposite sides of the rails and the head sections of insulation being also in staggered relation on opposite sides of the rails.

8. An insulated rail joint comprising the meeting ends of two rails, splice bars, insulation between the splice bars and the rails, a tie plate under each rail end and in electrical contact therewith, said tie plates being electrically disconnected from each other, one of said tie plates being connected to one splice bar and unconnected with the 110

other splice bar and each of said tie plates extending outwardly beyond the splice bar to which it is not connected.

10. An insulated rail joint comprising the meeting ends of two rails, splice bars, insulation between the splice bars and the rails, a tie plate under each rail end and in electric contact therewith, said tie plates being electrically disconnected from each other, one of said tie plates being connected to one splice bar and unconnected with the other splice bar and each of said tie plates extending

outwardly beyond the splice bar to which it is not connected, and each of said tie plates being formed with a shoulder adapted to engage one longitudinal edge of the base of the rail with which it is in contact.

In testimony whereof I hereunto affix my signature in the presence of two witnesses.

LAWRENCE GRIFFITH.
